FLUSH VALVE

Holden Phillip Ballou, Hartford, Conn., assignor
of fifty per cent to Nan Griffith Hynes, Hart-
ford, Conn.

Application December 8, 1936, Serial No. 114,853

4 Claims. (Cl. 4—57)

The present invention relates to new and useful improvements in flush valves for toilets and has for its primary object to provide, in a manner as hereinafter set forth, a device of this character embodying a novel construction and arrangement through the medium of which the closing of the valve will be hydraulically controlled.

Another very important object of the invention is to provide a toilet flush valve of the aforementioned character wherein the closing thereof will occur while a predetermined quantity of water is still in the tank thereby assuring comparatively quiet operation.

Still another very important object of the invention is to provide a toilet flush valve of the character described embodying a novel construction of valve member whereby leakage will be positively prevented when said member is seated.

A still further important object of the invention is to provide a flush valve for toilets which may be expeditiously installed for operation in flush tanks without the necessity of materially altering said tanks.

Other objects of the invention are to provide a flush valve for toilets which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a flush valve constructed in accordance with the present invention.

Figure 2 is a view in rear elevation thereof.

Figure 3 is a view principally in vertical section, taken substantially on the line 3—3 of Fig. 2.

Figure 4 is a view in vertical section through the cylinder, showing the piston mounted therein.

Figure 5 is a detail view in plan of the clamp which is mounted on the outlet pipe of the flush tank.

Referring now to the drawings in detail, it will be seen that the reference numeral 1 designates an outlet pipe to the bowl (not shown), said outlet pipe entering the flush tank through the bottom 2 thereof. In its upper end portion the pipe 1 is formed to provide a seat 3. A flange 4 is formed on the upper end portion of the pipe 1, said flange having formed therein a channel 5.

The reference numeral 6 designates a substantially U-shaped clamp which is mounted in the channel 5, said clamp being secured in position through the medium of a set screw 7. Mounted for swinging movement in a vertical plane on the clamp 6 is an angular lever 8, said lever being substantially square in cross section. The free end of the lever 8 is connected by a rod 9 to the usual hand operated lever (not shown) of the flush tank.

Rigidly secured beneath the lever 8 for engagement on the seat 3 is a valve member which is designated generally by the reference numeral 10. The valve member 10 includes a bowl 11 of suitable material having a centrally located opening 12 therein, said bowl being secured to the lever 8 by screws 13. The upper portion of the bowl 11 has formed thereon an external flange 14 having a groove 15 therein. It will be noted that the lower wall of the groove 15 is bevelled. Reference numeral 16 designates a cushion of suitable resilient material, preferably rubber, which is mounted beneath the bowl 11 and which has its marginal portion secured in the groove 15 by a suitable clamp 17. It will be noted that the cushion 16 extends from the lower portion of the bowl 11 to the periphery of the flange 14 in a manner to provide, in conjunction with said bowl, a pocket or chamber 18. As illustrated to advantage in Fig. 3 of the drawings, the construction and arrangement is such that the cushion 16 contacts the seat 3 at a point where said cushion is spaced from or free of the bowl 11.

The reference numeral 19 designates an arm which is mounted horizontally on an upper portion of the usual overflow pipe 20 of the flush tank through the medium of a suitable clamp 21. Pivotally mounted for swinging movement in a vertical plane on the free end of the arm 19 is a cylinder 22 which is open at its top. The bottom 23 of the cylinder 22 (see, Fig. 4) has formed therein a centrally located water outlet opening 24. Mounted for reciprocation in the cylinder 22 is a piston 25 which is connected by a rod 26 to the lever 8. The rod 26 enters the cylinder 22 through the opening 24 in the bottom 23 thereof, said opening being of a greater diameter than said rod. In its upper portion, the cylinder 22 is provided with circumferentially extending openings 27 which, in addition to admitting water, break the partial vacuum or suction created in said cylinder by the piston 25 as said piston passes said openings in its upward movement or stroke.

It is thought that the operation of the inven-

tion will be readily apparent from a consideration of the foregoing. When the toilet is to be flushed, the lever 8 is swung upwardly for disengaging the valve member 10 from the seat 3 thus permitting the water to flow from the tank through the pipe 1. As the lever 8 is thus swung upwardly, the piston 25 is moved upwardly in the cylinder 22 creating a suction or partial vacuum in said cylinder and drawing a certain quantity of water thereinto through the opening 24. The pivotal mounting of the cylinder 22 on the arm 19 permits said cylinder to readily adjust itself to meet various conditions in addition to compensating for the arc described by the swinging lever 8. As the piston 25 passes the openings 27 in its upward movement the suction or partial vacuum is broken and water rushes into said cylinder through said openings 27. When the lever 8 is released, said lever, with the valve member 10, begins to move toward closed position by gravity. After the piston 25 passes the openings 27 on its downward stroke the water is trapped in the cylinder 22 and can only escape through the restricted opening 24 thereby assuring a slow but steady and positive closing of the valve. The speed at which the valve closes will be governed by the size of the opening 24. Further, the construction and arrangement is such that the valve will be fully closed before the water in the flush tank drops to the level of the upper end of the outlet pipe 1. The chamber or pocket 18 in the valve member 10 permits the cushion 16 to readily yield when it contacts the seat 3 to assure positive closing at all times.

It is believed that the many advantages of a flush valve constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A valve for flush tanks comprising an outlet pipe extending into a flush tank through the bottom thereof, a seat in the upper end portion of said outlet pipe, an external flange on said upper end portion of said outlet pipe, said flange having a circumferential channel therein, a substantially U-shaped clamp engaged in the channel, a set screw threadedly mounted in one portion of the clamp and engaged in the channel for securing said clamp therein, an angular lever pivotally mounted on the clamp, a valve member mounted on said lever and engageable on the seat, and means for actuating the lever.

2. A flush valve comprising a seat, and a valve member engageable on said seat, said valve member including a bowl comprising an external flange on its upper portion having a circumferential groove therein, and a cushion mounted beneath the bowl and extending over the flange and secured in the groove, said cushion being adapted for contact with the seat and, in conjunction with the bowl, defining a chamber between the flange and the central portion of the bowl.

3. A flush valve comprising a seat, a lever, a valve member mounted on said lever and engageable with the seat, means for actuating the lever for disengaging the valve member from the seat, said valve member being operable by gravity toward the seat, and hydraulic means for controlling the return movement of the valve toward the seat, the last named means including a cylinder open at one end and closed at its other end, the closed end of said cylinder having a port therein, said cylinder having openings in the walls thereof, a piston mounted for reciprocation in the cylinder, and a rod connecting the piston to the lever, said rod passing through the port, said piston constituting means for drawing a fluid into the cylinder when the valve is opened and for expelling said fluid from said cylinder when the valve is closed.

4. In combination with a flush tank including an overflow pipe, a water outlet pipe extending into the tank through the bottom thereof, a seat in the upper end portion of said outlet pipe, an external flange on the upper end of the outlet pipe having a circumferential channel therein, a substantially U-shaped clamp secured in the channel, an angular lever pivotally mounted on the clamp for swinging movement in a vertical plane, a valve member mounted on said lever and engageable on the seat, means for raising the lever for lifting the valve member off the seat, an arm projecting horizontally from the overflow pipe, a cylinder mounted for swinging movement in a vertical plane on the free end of said arm, said cylinder being open at one end and closed at its other end, said cylinder having a port in its closed end and further having openings in its walls adjacent its open end, a piston operable in the cylinder, and a rod extending through the port and connecting said piston to the lever, the cylinder being adapted for the reception of water from the flush tank, the piston being controlled by the water in the cylinder for controlling the movement of the valve member toward closed position.

HOLDEN PHILLIP BALLOU.
